ATTORNEY

UNITED STATES PATENT OFFICE.

FREDERIC H. PARKE, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

COMPRESSOR-CONTROLLING DEVICE.

Application filed October 26, 1927. Serial No. 228,775.

This invention relates to controlling mechanism for a fluid compressor, and more particularly where the compressor is directly connected to be driven by an internal combustion or oil engine as employed for operating a locomotive or other vehicle.

When the vehicle is standing at a stop or descending a grade, the engine continues running at the usual slow idling speed and the compressor then runs at a corresponding slow speed.

Due to the slow speed at which the compressor runs when the engine is idling, the rate at which fluid is compressed by the compressor is reduced below that obtained at the average running speed.

In order to increase the capacity of the compressor of the above type, the principal object of my invention is to provide means for automatically speeding up the engine and consequently the compressor under conditions where the engine is idling and the pressure of fluid compressed by the pump is below a predetermined degree.

In the accompanying drawing, the single figure is a diagrammatic view, principally in section of a fluid compressing apparatus embodying my invention.

In the drawing, the reference numeral 1 represents a fluid compressor having the usual compressing piston 2 and a discharge valve 3, past which fluid compressed by the compressor is supplied through pipe 4 to a main or storage reservoir 5.

Associated with the compressor is an unloading valve 6, which when opened, permits the compressor piston to reciprocate without compressing fluid into the storage reservoir 5. The valve 6 is provided with a stem 7 which projects out of the compressor casing and is engaged by the end of a lever 8 fulcrumed on a pin 9. The other end of the lever 8 is adapted to be operated by a flexible diaphragm 10, a follower 11 engaging the diaphragm, and a ball 12 being interposed between the follower and the end of the lever.

A controlling valve device is provided comprising a casing 13 having a piston chamber 14 containing a piston 15 and a valve chamber 16 containing a slide valve 17, the piston 15 having a stem 18 provided with flanges for operating said valve. The outer end of the

piston stem 18 carries a small piston 19, the chamber 20 at the outer face of which is open to the atmosphere through an atmospheric passage 21.

Associated with the valve device is a magnet valve device comprising a magnet 22 adapted to control the operation of double beat valves 23 and 24.

The rod 25 is adapted to operate the usual throttle valve (not shown) of the internal combustion engine (not shown), which drives the locomotive or vehicle, and is provided with an operating lever 26, said lever being pivoted on a pin 27 and having a pin 28 which engages in a slot 29 provided at the end of the rod 25. The outer end of the lever 26 is provided with a contact 30 and in the idling position of the lever, said contact connects contacts 31 and 32 so as to complete a circuit including the magnet 22 and a source of current 33.

A piston 34, contained in a cylinder 35, is provided for also operating the rod 25 and for this purpose the piston is provided with a stem 36 which is pivotally connected to one end of a lever 37. Said lever is pivotally mounted on a pin 38 and the opposite end of the lever carries a pin 39 which engages in a slot 40 in the rod 25. The piston chamber 41 at one side of piston 34 is connected by a pipe 42 to a chamber 43 intermediate the valves 23 and 24.

A governor device is provided comprising a casing 44 containing a cut-out piston 45 subject to the pressure of a coil spring 46 and carrying a valve 47 and a cut-in piston 48, subject to the pressure of a coil spring 49, and carrying a valve 50.

In operation, with the throttle lever 26 in its idling position, as shown in the drawing, a circuit is closed through magnet 22, so that said magnet is energized and the valve 23 is held seated while the valve 24 is held unseated.

If the pressure in the reservoir 5 is less than a predetermined degree, the pistons 45 and 48 of the governor device will be operated by the springs 46 and 49 to seat the valves 47 and 50.

With the valve 50 seated, the piston chamber 14 of the controlling valve device will be vented to the atmosphere through pipe 51,

passage 52, and past the upper end of piston 48 to passage 53 which is open to the atmosphere.

The valve chamber 16 is supplied with fluid 5 under pressure from reservoir 5, through pipe 54 and passage 55, so that with atmospheric pressure in piston chamber 14, the fluid pressure in valve chamber 16 will shift the piston 15 to its outer position. In this position, the 10 valve chamber 56 containing the valve 24 is connected to the valve chamber 16 through passage 57.

Fluid under pressure is thus supplied to valve chamber 56 and thence flows past the 15 open valve 24 to piston chamber 41. The piston 34 is then moved outwardly so as to cause the rod 25 to be shifted and thereby the throttle valve of the engine is opened wider, so that the engine is speeded up. The compressor 1 being directly connected to the 20 engine, is also speeded up, so that the compressor operates to compress fluid into the reservoir 5 at a greater rate.

In the above described position of slide 25 valve 17, a cavity 58 connects passage 60, leading to pipe 4, to an exhaust port 59, so that diaphragm chamber 61 of the unloader diaphragm 10 is subject to atmospheric pressure. With atmospheric pressure in chamber 61, the spring 62 acts to hold the valve 6 seated, so that the compressor is operative to compress fluid into the reservoir 5.

When the pressure in the reservoir 5 has been increased to a predetermined degree the 35 valve 47 of the governor device will be lifted against the pressure of spring 46, so that fluid under pressure is supplied from the reservoir through a passage 63 to the chamber at the outer seated area of the piston 48. This pressure added to the pressure always acting on the seated area of the valve 50 is sufficient to cause the piston 48 to be moved upwardly, 40 unseating the valve 50. The exhaust passage 53 is cut off by this movement and communication is opened from the reservoir 5, through a passage 64, to pipe 51 and piston chamber 14.

Fluid under pressure supplied to said chamber then shifts piston 15 to its inner 50 position, in which passage 57 is connected through cavity 58 with exhaust port 59. If the lever 26 is still in its idling position, and the magnet 22 energized so that valve 24 is unseated, fluid under pressure will be vented 55 from piston chamber 41, permitting the spring 65 to shift the piston to its outer position. The corresponding movement of the lever 37 then permits the rod 25 to move back to its usual idling position.

The movement of slide valve 17 to its inner 60 position, as above described, causes passage 60 to be uncovered, so that fluid under pressure is supplied from valve chamber 16, through passage 60 and pipe 4 to diaphragm 65 chamber 61. The diaphragm 10 is then moved

by the pressure in chamber 61, so as to operate the lever 8 and effect the unseating of the valve 6. The compressor 1 then runs without load and without compressing fluid into the reservoir 5.

When the throttle control lever 26 is moved away from its idling position, the circuit of the magnet 22 is opened, so that the magnet 22 becomes deenergized, permitting the valve 24 to seat and the valve 23 to unseat. The 75 piston chamber 41 is then connected to exhaust port 66, so that piston 34 is held in its inoperative position by spring 65.

The valve 24 being held closed, movement 80 of the controlling valve device 13 is rendered ineffective to control the operation of piston 34.

The lost motion slot 40 in rod 25 permits movement of the throttle rod by operation of the lever 26 without moving the lever 37, and the lost motion slot 29 permits movement of the rod 25 by operation of piston 34 without movement of the lever 26.

With the above described construction, the compressor is only speeded up when the lever 90 26 is in its idling position and also only when the pressure in the storage reservoir has been reduced to a point which causes the governor device to move to its cut-in position.

While one illustrative embodiment of the 95 invention has been described in detail, it is not my intention to limit its scope to that embodiment or otherwise than by the terms of the appended claims.

Having now described my invention, what 100 I claim as new and desire to secure by Letters Patent, is:—

1. The combination with an engine driven fluid compressor, of means for effecting the acceleration of the engine and having an idling position, and mechanism operative only with said means as in the idling position for accelerating the speed of the engine and thereby the speed of the compressor.

2. The combination with an engine driven fluid compressor, of a hand operated member for effecting the acceleration of the engine and having an idling position, and means under the control of said member and operating automatically upon movement of said member to its idling position for accelerating the speed of the engine and thereby the speed of the compressor.

3. The combination with an engine driven fluid compressor, of a member operative to effect the acceleration of the engine, hand operated means for operating said member and having an idling position, a governor device controlled by the pressure of fluid compressed by the compressor for controlling the operation of said member, and means operative upon movement of said hand operated means to the idling position for rendering said governor device effective.

4. The combination with an engine driven

fluid compressor, of a member operative to effect the acceleration of the engine, hand operated means for operating said member and having an idling position, a governor device 5 controlled by the pressure of fluid compressed by the compressor for controlling the operation of said member, and means for cutting said governor device into operation upon movement of said hand operated means to 10 its idling position.

5. The combination with an engine driven fluid compressor, of a member operative to effect the acceleration of the engine, hand operated means for operating said member and 15 having an idling position, a governor device controlled by the pressure of fluid compressed by the compressor for controlling the operation of said member, and means operative only when said hand operated means is in the 20 idling position to permit said governor device to control the operation of said member.

6. The combination with an engine driven fluid compressor, of a member operative to effect the acceleration of the engine, hand 25 operated means for operating said member and having an idling position, auxiliary controlling means for effecting the operation of said member, a governor device controlled by the pressure of fluid compressed by the 30 compressor for controlling the operation of said auxiliary controlling means, and means operated upon movement of said hand controlled means to the idling position for rendering said auxiliary controlling means effective. 35

7. The combination with an engine driven fluid compressor, of means for unloading the compressor, a member operative to effect the acceleration of the engine, means for effecting the operation of said member, and a 40 governor device controlled by the pressure of fluid compressed by the compressor for effecting the operation of said member and said unloading means.

8. The combination with an engine driven fluid compressor, of fluid pressure operated means for effecting the loading and unloading of the compressor, a member operative to effect the acceleration of the engine, fluid pressure operated means for operating said member, 45 a valve device for controlling the fluid pressure for operating both said fluid pressure operated means, and a governor device controlled by variations in pressure of fluid compressed by the compressor for controlling 50 the operation of said valve device.

9. The combination with an engine driven fluid compressor, of a member for effecting the acceleration of the engine, hand operated means for operating said member, auxiliary 55 means controlled by variations in pressure of fluid compressed by the compressor for also controlling the operation of said member, and electrically controlled means controlled by said hand operated means for rendering said auxiliary means effective or ineffective to control the operation of said member.

In testimony whereof I have hereunto set my hand.

FREDERIC H. PARKE.
